Application March 14, 1952, Serial No. 18,886

Term of patent 14 years

(Cl. D7--7)

To all whom it may concern:

Be it known that I, André Perugia, a citizen of Italy, residing at Paris, France, have invented a new, original, and ornamental Design for a Lady's Shoe or Similar Article, of which the following is a specification, reference being had to the accompanying drawing, forming part thereof.

In the drawing:

Fig. 1 is a front perspective view of a lady's shoe, showing my new design; and

Fig. 2 is a side view thereof.

The essential features of the design are shown in full lines.

I claim:

The ornamental design for a lady's shoe or similar article, substantially as shown and described.

ANDRÉ PERUGIA.
